UNITED STATES PATENT OFFICE.

DANIEL L. STEVENS, OF LYONS, IOWA.

SAW-SHIFTING MECHANISM FOR GANG-EDGERS.

SPECIFICATION forming part of Letters Patent No. 296,360, dated April 8, 1884.

Application filed January 15, 1884. (No model.)

To all whom it may concern:

Be it known that I, DANIEL L. STEVENS, a citizen of the United States of America, residing at Lyons, in the county of Clinton and State of Iowa, have invented certain new and useful Improvements in Levers for Shifting Saws on Edgers and other Devices for Cutting Lumber, of which the following is a specification, reference being had to the accompanying drawings.

My invention relates to devices for shifting saws in edging-machines; and it consists of the construction and combination of the devices which are embraced in the claims, and are hereinafter fully set forth.

In the drawings, Figure 1 is a longitudinal section of the shifter. Fig. 2 is a perspective view of the same. Fig. 3 is a perspective view of a portion of the lever-plate detached. Fig. 4 is a perspective view of one of the guide-pin blocks detached.

A designates a saw mounted on its arbor A'.

B is a bifurcated head, connected at B' to the plate B² by a pivotal or hinged joint adapted to enable the head to be raised away from the saw, as shown by dotted lines in Fig. 1. The plate B² is provided with the longitudinal slots a a, to receive the bolts C D, by which the plate is fastened to the lever, and is constructed with the offset or step b, to extend the plate and its connecting-lever downward and under the rollers P P, which carry the lumber R to be edged, as seen in the drawings.

F is the lever portion of the shifter, provided with the transverse slot O and the pivotal studs E' c and the gage-dog G.

H designates blocks provided with the guide-pins L. One of these blocks is attached to each prong of the head B by a single bolt, N, extended vertically through holes in the center of the block and through the prong, to allow lateral oscillatory movements of the blocks, so as to adjust the guide-pins to the position of the saw. The bearing-shoulders and ends of the joint by which the head B and plate B² are connected are beveled, as shown, to hold the head firmly when in position for use.

K is a bed-piece, to which is bolted the frame or yoke a', which is provided with the set-screw E. The lever-plate F is extended through this yoke, in position for the inner end

of the set-screw to have its bearing in a cavity in the upper end of the stud E', the lower pointed end of the lower stud, c, having its bearing in a cavity in a stud, M, on the bed-plate K, or in a cavity in the lower plate of the yoke.

J is a gage-bar provided with notches d the requisite distance apart to receive the dog G. The longitudinal slots a a in the plate B² enable the shifter to be adjusted in length to adjust it to the position of the saw without changing the positions of the bed-plate K and gage-bar J. The transverse slot O in the lever-plate F allows lateral adjustment of the end of the plate B², which, combined with the oscillatory movements of the pivoted blocks H, carrying the guide-pins, enables the operator to adjust the bifurcated head in line with the saw sufficiently to avoid binding or unnecessary friction of the guide-pins against the saw in all the different positions in which the lever may be required to be placed in shifting the positions of the saw. By means of the pivoted bearings of the lever and the gage-dog and bar, the lever is readily oscillated and adjusted to the required position to set the saw to cut the lumber the required width.

Having described my invention, I claim—

1. The combination of the bifurcated head B, plate B², lever F, and the guide-pin blocks H, pivoted centrally to the bifurcated head, substantially as and for the purposes described.

2. The combination of the plate B², lever F, pivoted blocks H, guide-pins L, and the bifurcated head B, connected to the plate B² by a joint adapted to enable the entire head to be raised away from the saw, substantially as and for the purposes set forth.

3. The combination of the hinged bifurcated head B, the pivoted blocks H, having the guide-pins L, the lever F, and the plate B², jointed to the bifurcated head and to the lever, and provided with the offset b, substantially as and for the purposes described.

4. The combination, with the lever-plate F, having the transverse slot O, of the bifurcated jointed head B, pivoted blocks H, guide-pins L, and the plate B², provided with the longitudinal slots a a, substantially as and for the purposes set forth.

5. The combination of the pivoted blocks

H, pins L, bifurcated jointed head B, plate B², provided with longitudinal slots a a, the lever F, provided with the transverse slot O, and pivotal studs E' c, the yoke a', provided with 5 the set-screw E, the dog G, and the notched gage-bar J, substantially as and for the purposes described.

In testimony whereof I hereunto affix my signature in presence of two witnesses.

DANIEL L. STEVENS.
